GAME BOARD AND CARDS ADAPTED TO BE
UTILIZED THEREWITH

Woodrow A. Heacock, Los Angeles, Calif.

Application October 2, 1945, Serial No. 619,813

13 Claims. (Cl. 273—131)

1

My invention relates to games and game boards, and has particular reference to a novel game to be played with playing pieces movable along prescribed paths over a game board divided into a plurality of playing areas.

It is an object of my invention to provide a game of simple construction which may be played by three or more players moving playing pieces over a prescribed course on a field of play on a game board which is divided into a plurality of playing areas.

Another object of my invention is to provide a game of the character described, wherein the playing pieces are constructed of two or more different sizes to denote different valuations of the playing pieces, and denoting the possible extent of movement permitted the pieces of different valuation.

Another object of my invention is to provide a game board which may be constructed of sheet material in the form of a plurality of sheet sections of relatively small area hingedly connected to each other to permit unfolding of the board into a playing field of relatively large area, and to permit the folding of the board into a substantially flat, compact package of lesser area for storage and transportation purposes.

Another object of my invention is to provide in combination with the playing field and pieces set forth in the preceding paragraphs, a plurality of cards divided into sets or groups of four cards each, each of the sets or groups being designated by a numeral denoting the group or set, while on the reverse side of such cards appears indicia denoting the area of the game board to which a player receiving the card will direct the movement of his playing pieces.

Other objects of my invention will be apparent from the study of the following specifications read in connection with the accompanying drawings, wherein:

Fig. 1 is a perspective view of a game board defining a playing field and having located thereon a plurality of sets of playing pieces arranged on the board in the initial starting positions of the pieces of all of the players;

Fig. 2 is a perspective view of the game board shown in Fig. 1 illustrating the manner in which the game board is divided into a plurality of relatively small area sections hinged together for folding; and

Fig. 3 is a view of a plurality of the cards which may be employed in playing the game shown in Fig. 1.

Referring to the drawings, I have illustrated

2

in Fig. 1 a game board 1 which may be constructed of any suitable sheet material such as cardboard, wood, or the like, the board being divided into a plurality of contiguous outlined areas such as indicated at 2, certain of the adjacent areas adjacent the center of the board being designated by letters or other indicia 3 as an objective area or zone toward which playing pieces 4 and 5 are to be moved during the playing of the game.

The central objective areas denote territory to be occupied by playing pieces as the game progresses, while the playing pieces 4 and 5 are preferably divided into four groups, each group containing a plurality of small sized pieces 4 and two or more larger sized pieces 5. Each of the groups of playing pieces are distinguished from each other either by distinguishing coloring or by marking, or other indicia appearing upon each 20 of the playing pieces.

At the start of the game each player arranges the playing pieces of the group of his selection, in the outermost squares 2 of the game board adjacent to the position of the player.

25 One of the players then cuts the cards. The number of the card selected will designate the set or group of four cards to be used in the play of the game, and the cards of that set are then dealt to each of the players.

30 In view of the fact that each set or group of four cards bearing the same numeral will contain two cards bearing one zone designation and two other cards bearing another zone designation, the dealing of the cards automatically pairs up two of the players as a team whose objective is the same zone as designated by one pair of the cards in the group, while the other two players are teamed up with an objective of another of the zones as designated by the two remaining 40 cards of the set.

The player to the left of the dealer then starts the play by moving one of the game pieces toward the objective designated by the card dealt to him, it being understood that each of the players keeps confidential the information as to the objective zone toward which he is to move his playing pieces so that neither his partner nor the other two "enemy" players know what zone 50 is the objective of the first player.

It will be recalled that the playing pieces 4 were of smaller dimensions than the playing pieces 5, so as to distinguish these pieces from each other, the playing pieces 4 having prescribed courses of travel or distances of travel

upon each play different from those ascribed to the playing pieces 5.

For example, the playing pieces 4 may move either forwardly or backwardly from one square to another, or sidewise in either direction from one square to another, or the pieces may move diagonally in any direction from one square to another, but the small pieces 4 are permitted to move a distance of only one square upon each play. The larger pieces 5 may move either forwardly, rearwardly, sidewise in either direction, or diagonally in any direction, and may move through any number of squares at a time, provided the path is not obstructed by the location of another playing piece in one of the squares through which it is desired to traverse the piece.

Various rules for the capture of an opponent's piece may be prescribed. For example, one player moving a playing piece into a square occupied by an opponent's playing piece, may be said to capture the opponent's playing piece, and in such instance, the smaller or minor pieces might be permitted to capture only minor pieces belonging to an opponent, while major pieces or larger playing pieces may be permitted to capture either major or minor pieces belonging to an opponent.

Since, by reason of the dealing of the cards each player is unaware as to which other player is his team mate and which of the other players is his opponent, the arrival of two pieces belonging to different players in a given zone, may require the player of the last piece to so arrive, to declare whether or not the player of the other piece is his partner. If the guessing player guesses correctly, that team wins the game, while if the guess is wrong, the play continues until the objective zone for one team is occupied by four of the team's playing pieces; or, in the event the total number of playing pieces remaining to the partners of a single team is less than four, then occupancy of the objective zone by a greater number of playing pieces than are located in the objective zone of the opposing team, may be construed as capture of the objective zone and the winning of the game.

To permit a relatively large playing field to be used, I prefer to make the playing field of a plurality of rectangular section 1a, 1b, 1c and 1d hinged together in such fashion as to permit the ready folding of the sections upon each other to comprise a compact, flat package of substantially small area. For example, the sections 1a and 1d may be hinged together, while the sections 1b and 1c are hinged together, and the two sets of hinged sections may be joined by means of a hinge interconnecting the sections 1a and 1b.

While I have shown and described the preferred embodiment of my invention, I do not desire to be limited to any of the details illustrated or described herein except as defined in the appended claims.

I claim:

1. In a game, the combination of a playing field divided into a plurality of contiguous outlined areas including at the center of the playing field a plurality of adjacent ones of said areas defining a plurality of adjacent objective zones, each zone including more than one of said areas and bearing a symbol differentiating said zone from adjacent objective zones, a plurality of sets

of playing pieces, one for each player adapted to be moved over the playing field toward an objective zone assigned to a player, and four cards, two of which bear on their faces a symbol corresponding to a symbol on one of said zones and two of which bear on their faces a symbol corresponding to a symbol on another of said zones, for designating to each player the objective zone toward which his playing pieces must move, and for pairing players as partners whose pieces are to be directed toward the same zone.

2. In a game, the combination of a playing field divided into a plurality of contiguous outlined areas including at the center of the playing field a plurality of adjacent ones of said areas defining four adjacent objective zones, each zone including more than one of said areas and bearing a symbol differentiating said zone from adjacent objective zones; a plurality of sets of playing pieces, one for each player adapted to be moved over the playing field toward an objective zone assigned to a player and each set containing more pieces than there are areas in a zone; and four cards adapted to be dealt to the players, two of which bear on their faces a symbol corresponding to a symbol on one of said zones and two of which bear upon their faces a symbol corresponding to a symbol upon another of said zones which designate to each player the objective zone toward which his playing pieces must move, said symbols corresponding to the symbols of two of the four zones to set up opposed objective areas.

3. In combination with a playing area having a plurality of objective zones each of which bears a symbol differentiating it from adjacent zones, a device for choosing partners secretly comprising a deck of cards arranged in sets differentiated from each other by indicia on the backs thereof and the cards of each set having symbols on the faces thereof correlated with the symbols of the objective zones, characterized by each set being correlated to at least two different objective zones, whereby partners are selected among more than two players by the distribution of the cards of one set to the players.
